UNITED STATES PATENT OFFICE.

GEORGE W. CLENDON, OF PIERMONT, NEW YORK, ASSIGNOR TO INTERNATIONAL COMBUSTION ENGINEERING CORPORATION, A CORPORATION OF DELAWARE.

PULVERIZED-FUEL-BURNING LOCOMOTIVE.

Application filed August 15, 1925. Serial No. 50,351.

This invention relates to pulverized fuel burning locomotives.

In the burning of pulverized coal in locomotive fire boxes considerable difficulty is encountered in connection with the honeycombing of the deposit over the flues, the flues being completely covered over in a comparatively short time, particularly with coal the fusing point of the ash of which is low.

10 One of the primary objects of my invention is to overcome this difficulty.

More specifically it is an object of the invention to provide and so arrange the evaporating elements of the boiler that the refractory particles are cooled sufficiently before they strike against the flue sheet to prevent this honeycombing.

Stated in another way, I propose by my invention to absorb heat from the flame 20 at such a rate that the furnace temperature is kept within limits, wherein the foregoing difficulty is not encountered, or at least greatly minimized; this without interfering with combustion.

25 The foregoing, together with such other objects as may hereinafter appear, or are incident to my invention, are realized by means of a construction which I have illustrated in preferred form in the accompanying drawings, wherein

Fig. 1 is a longitudinal section thru the rear portion of a locomotive equipped with my improvements;

Fig. 2 is a half cross section and half end 35 elevation to the fire box shown in Fig. 1, the end elevation being broken out to illustrate certain of the parts, and the figure being drawn on an enlarged scale;

Fig. 3 is an enlarged section taken on the 40 line 3-3 of Fig. 1, and

Fig. 4 is a fragmentary section taken on the line 4-4 of Fig. 1.

Referring now to Fig. 1 and Fig. 2, the reference letter A indicates the fire box of the locomotive, such fire box being composed of the outside and inside throat sheets 7 and 8; the inside side sheets 9; the inside back sheet 10; the crown sheet 11; the outside side sheets 12; the outside back sheet 13 and the roof or cover sheet 13a. Forwardly of the fire box proper is the barrel 14 constituting a continuation of the combustion space of the fire box, the forward end of such

combustion space being closed by the flue sheet 15 from which the flues 16 extend forwardly.

The bottom of the fire box is closed by the fire pan B, such fire pan being lined with refractory material 17.

The powdered coal is admitted thru one or more burners 18 extending into the rear wall of the fire pan, the fuel being directed forwardly toward the inclined front or flash wall of the fire pan, the refractory lining of such wall being carried up to cover the inside throat sheet 8. Above the burners is located an arch 19. The incoming fuel is thus subjected to radiant heat from the refractories, the fuel and flame stream first taking a forward course, then bending upwardly and then backwardly as will be further described. Air for combustion is admitted thru inlet openings 20 connecting with the air channel 21 extending around the fire pan.

A plurality of siphon water legs 22 connect the front water leg with the space above the crown sheet, the lower portions of such legs being rounded as indicated at 23 to support the arch 24 composed of refractory bricks. This arch serves to subject the fuel and flame stream to radiant heat and to turn or guide the fuel and flame stream rearwardly. The life of the bricks of the arch is extended by virtue of the cooling effect of the siphon water legs, thru which a very rapid circulation takes place.

Extending forwardly and upwardly from the inside back sheet 10 to the crown sheet 11 are a plurality of spaced tubes 25, such tubes carrying an arch 26, the upper end of which terminates adjacent the upper end of the forward arch. The lower end of the arch 26 terminates short of the inside back sheet and the sides terminate at the side arch tubes to provide a passage thru which fuel and flame stream may pass upwardly over the rear end and sides of the arch 26. The arch 26 is held in position by means of the spacer bricks 27 which rest upon the tubes 25 and are adapted to abut against the back sheet 10. The arch 26 and the arch 24, considered together, form an inverted V-shaped arch the forward leg of which abuts against the throat sheet 8 and the rear leg of which terminates short of the inside back sheet 10.

It will be noted that the fuel and flame stream takes a substantially U shaped path in the box defined by the fire pan, the two arches, and the side sheets of the fire box, such portion constituting a zone of intense temperature in which thorough mixture of fuel and air occurs with combustion well established and well progressed.

The flames passing over the rear end of the arch 26 travel forwardly passing first thru the spaces between the upper ends of the water tubes 25, from which the flames enter the barrel 14, in which I locate additional circulating tubes 28. The products of combustion must pass thru the space between such tubes on their way to the flues 16. It is to be noted that the tubes 25 extend between the siphon water legs 22. It will be seen that the upper ends of the tubes 25, the upper portions of the water legs 22 and the tubes 28 constitute a large addition to the evaporating surface of the fire box and such portions absorb a large quantity of heat so that by the time the products of combustion reach the flue 16 their temperature will be sufficiently low to prevent the refuse particles carried in suspension therein from coalescing together upon the flue sheet and eventually covering over the flues. This deposit remains in a readily removable form and is taken out thru one or more discharge openings 29.

It will be seen that the two arches constitute a barrier between the additional evaporating surface just described and the zone of intense temperature previously mentioned, in consequence of which the fuel and flame stream in such region of intense temperature is shielded from the additional evaporative surfaces which would otherwise unduly lower furnace temperature, producing improper combustion. Such additional evaporative surfaces, however, tend to prolong the life of the forward arch 24, which is an item of great importance in locomotive fire boxes.

In addition to overcoming the difficulty above mentioned, the arrangement is such as to greatly increase the steaming capacity of the locomotive because of the large amount of heat absorbed in the fire box nearest the source of the greatest heat. Furthermore, the contents of the boiler is turned over much more rapidly, which also tends toward increased capacity and also efficiency.

Other objects will occur to those skilled in the art.

What I claim is:

1. In a pulverized coal burning locomotive, a fire box, means for delivering fuel into said box in a forward direction adjacent the bottom thereof, an inverted V-shaped

arch in said box the rear leg of which terminates short of the rear wall of said box, an outlet above and forward of said arch, together with longitudinal channels largely defined by evaporative surfaces above said arch to substantially cool the fuel and flame stream before it reaches said outlet. 65

2. In a pulverized coal burning locomotive, a fire box, means for delivering fuel into said box in a forward direction adjacent the bottom thereof, an inverted V-shaped arch in said box the rear leg of which terminates short of the rear wall of said box, an outlet above and forward of said arch, longitudinal channels largely defined by evaporative surfaces above said arch, together with additional evaporative surfaces comprising tubes beyond said arch but rearward of said outlet. 70 75 80

3. In a pulverized coal burning locomotive, a fire box, means for delivering fuel into said box in a forward direction adjacent the bottom thereof, an inverted V-shaped arch in said box the rear leg of which terminates short of the rear and sides of said box, together with longitudinal channels largely defined by evaporative surfaces above said arch to substantially cool the products of combustion before they reach the outlet. 85 90

4. In a pulverized coal burning locomotive, a fire box an outlet in an upper forward portion thereof, means for delivering the coal into said box in a forward direction adjacent the bottom thereof, siphon legs in said box, water tubes in said box, together with an arch supported by said siphon legs and said tubes whereby the fuel and flame stream is caused to contact serially with the lower portions of said legs, said tubes, the upper sheet-like portions of said legs and then to pass to said outlet. 95 100

5. In a pulverized coal burning locomotive, a fire box having an outlet in a forward portion thereof and means for delivering the fuel into said box in a lower rearward portion thereof, water tubes in a rearward portion of said box, siphon legs extending forwardly of said tubes, other tubes between said legs and said outlet, together with an inverted V-shaped arch supported by said legs and said first mentioned tubes whereby the fuel and flame stream is caused to contact serially with the lower portions of said legs, said first mentioned tubes, the upper portions of said legs and said last mentioned tubes. 105 110 115

In testimony whereof, I have hereunto signed my name.

GEORGE W. CLENDON.
